UNITED STATES PATENT OFFICE.

WALTER CLARK BARROWS, OF HARTFORD, CONNECTICUT.

GAME APPARATUS.

1,332,021.

Specification of Letters Patent. Patented Feb. 24, 1920.

Application filed June 19, 1919. Serial No. 305,321.

To all whom it may concern:

Be it known that I, WALTER CLARK BARROWS, a citizen of the United States, residing at Hartford, in the county of Hartford and State of Connecticut, have invented new and useful Improvements in Game Apparatus, of which the following is a specification.

The object of the invention is to provide a simple and entertaining topical toy for game apparatus adapted in an essential feature of the method of operation to portray the action of a submarine mine upon a vessel and to this end the same consists of a combination of parts, it being understood that changes in form or proportion may be resorted to within the scope of the appended claims without departing from the principles involved.

20 In the drawings:

Figure 1 is a plan view of the apparatus.

Fig. 2 is a longitudinal section of the same.

Fig. 3 is a transfer sectional view of the apparatus on the line of the pivot of the tilting element.

The playing board 10 is built substantially on the plan of the well known Tivoli board in that it is disposed at a slight downward inclination from the starting end 11 toward the above end 12, and is provided at intermediate spaced points with obstacles 13, consisting in this instance of angular blocks for diverting and interfering with the direct progress of the playing object 14, such as a ball or marble as shown, and is provided at a point, well guarded by said obstacles with a goal 15 which in this instance consists of an opening in the playing board 40 of a size sufficient to receive the playing object.

This playing board forms preferably the top of a box or inclosure 16 constituting a runway which is open at the lower end 45 as shown at 17 so as to permit of access toward and withdrawal of the playing object from the runway after each play, it being understood that said object in the course of play is positive upon and released at the upper or starting end 11 of the board and is then permitted to find its way along the surface of the board between the obstacles 13 with the purpose of having it reach and enter the goal formed by the opening 15.

55 Disposed at or near the lower or base end of the playing surface is an indicator con-

sisting of the representation of a modern vessel such as a submarine or torpedo boat or man-of-war, formed in series comprising a base or rest 18 and a superstructure 19 adapted, preliminary to play to be deposited upon the base or rest which is provided at a suitable intermediate point with a preferably elongated opening or slot 20 communicating with the interior of the runway. 60 This slot or opening in the seat or base is designed to permit of the movement of a plunger 21 carried by a lever or other tilting element 22, for example at 23, and provided at the opposite end from the 70 plunger with a plate or table 24 arranged beneath the goal opening 15 and in the path of the playing object as it enters the runway through said opening.

Thus, in the operation of the device, the 75 movable element of the indicator having first been deposited upon the stationary element thereof formed by the base or seat, the successful operation of the playing object, represented by having it traverse the 80 obstructed portion of the playing field or surface and enter the goal, will cause the tilting of the lever by the impact of the playing object upon the table or plate adjacent to the goal opening, and hence the 85 forward projection of the plunger to displace the movable element of the indicator in simulation of the blowing up of the vessel by means of a mine. Obviously the obstacles and the goal as well as the idea of 90 the rest or base forming the closure for the lower end of the playing board may be provided with scoring marks or characters to be claimed respectively by the players engaged in the game. 95

The invention having been described, what is claimed as new and useful is:

1. A game apparatus having an inclined playing board provided with surface obstacles and a goal consisting of an opening adapted for the reception of a rolling playing object, an indicator having a displaceable element, and a seat or base for normally supporting the same, a plunger for movement relative to the seat or base for engagement with and displacement of said movable element and depressible means operatively connected with the plunger and located adjacent to said goal opening for actuation by the playing object on entering 100 105 110 said opening.

2. A game apparatus having a playing

field for traverse by a rolling object and provided with surface obstacles and a goal opening for the reception of the playing object, an indicator, a seat or base and a displaceable element for normal occupation of the seat or base, a plunger extending through an opening in the seat or base for engagement with the movable element, and a tilting lever connected with said plunger and having a table or plate located in the path of an object entering said opening in the playing field.

3. A game apparatus having a playing field for traverse by a rolling object and provided with surface obstacles and a goal

opening for the reception of said object, an indicator consisting of a base and a displaceable element jointly constructed to represent a modern vessel, said base being disposed to close the end of the playing field, a plunger movably arranged in an opening in the base for terminal contact with and displacement of said element seated thereon, and a movable table or plate operatively connected with said plunger and arranged adjacent to said goal opening for actuation by the playing object entering said opening.

In testimony whereof I affix my signature.

WALTER CLARK BARROWS.
